LLP

(57) **CLAIM**

The ornamental design for a chair, as shown and described.

DESCRIPTION

FIG. 1 is a front perspective view of a chair, showing my new design;

FIG. 2 is front view thereof;

FIG. 3 is rear view thereof;

FIG. 4 is a side view thereof;

FIG. 5 is another side view thereof, from a side opposite that of FIG. 4;

FIG. 6 is a top view thereof;

FIG. 7 is a bottom view thereof;

FIG. 8 is another front perspective view thereof, from a different angle than FIG. 1; and,

FIG. 9 is rear perspective view thereof.

1 Claim, 9 Drawing Sheets
